UNITED STATES PATENT OFFICE

2,357,279

BLOWER

Max Rendelstein, Brussels, Belgium; vested in the
Alien Property CustodianApplication October 25, 1939, Serial No. 301,295
In Belgium October 24, 1938

1 Claim. (Cl. 230—113)

This invention relates to means for increasing the effective output of the propellers, of aeromotors and of similar rotating devices. It is known that the effective output of such devices is based on the resistance offered by the fluid in which the device under consideration functions. Starting from the ascertainment of the fact that the effective output can be increased with the density of the medium, the process according to the invention consists essentially in producing alternate compression and relaxation or expansion of the fluid on all sides of the device, as the device rotates.

In the following description, for simplicity's sake, one will suppose that the invention concerns a bladed screw or propeller revolving in the air, but the invention is applicable to any rotative device revolving in any fluid medium whatever.

The process according to the invention will be described with reference to the annexed drawing which represents some devices, given as non-limitative examples, for the realization of the process. On the drawing,

Fig. 1 shows a vertical section of a device constructed in accordance with the invention, and

Fig. 2 shows it in vertical section taken along the line 2—2 of Fig. 1.

Fig. 3 shows schematically another form of embodiment of the device,

Fig. 4 shows a front view of a perforated disc which forms part of the device shown in Figure 3.

Fig. 5 shows the invention applied to an aeroplane.

According to Figs. 1 and 2, a bladed screw or propeller 4 is keyed on the shaft 5 which is operated by means of the pulley 6 and the belt 7. A cellular wheel 10 is provided on either side of the propeller, consisting of a rim 1 and of the radial partitions 2 which start at the hub 3 and divide the wheel in compartments 9. The cellular wheels are fixed on a base 8 and their hubs act as bearings for the shaft 5. The propeller 4 owing to its revolutions produces a current of air in the direction of the arrow P. Owing to the presence of the cellular wheels on either side of the propeller 4, the flow of this current of air is modified in density at very frequent intervals as the propeller rotates because the air has a tendency to be compressed while confined in the cells 9. As the relatively dense or compressed bodies of air leave the cells, pulsations which are short-lived, follow one another continually, the result being an increase of the effective output of the propeller, because of the expanding

effect of the said bodies of air as they escape from the cells 9.

The width of the propeller blades, or the depth of the cells is advantageously regulated, and for this purpose each cellular wheel can, for instance, be made of two similar parts which telescope one in the other in a radial direction, which allows the optimum depth of the cells to be determined in each case.

- 10 10 A further embodiment of the invention is schematically shown in Fig. 3. A ventilator 17 exhausts the air of chamber 13 by means of a conduit 15 in the direction of the arrow R, and delivers it, always in the direction of the arrow 15 R, through the conduit 16 into the chamber 14. Before the open terminal face of each of the chambers 13 and 14 is a pair of stationary cellular wheels 10, fixed on a base 8 and in which turns a shaft 5, which rotatably supports a disc 11 provided with windows 12 (Fig. 4) revolving between the wheels 10 of each pair. The shaft 5 is mounted, for instance, in the hubs 3 of the cellular wheels, and is operated by means of a pulley 6 and a belt 7. Owing to the rotation of 20 the discs 11, the current of air circulating as shown by the arrows R is periodically interrupted which gives rise to a rapid succession of compressions and expansions in the current of air. The device represented may serve, for instance, as a compressor, or as a blower, and allows notably large masses of air to be delivered with a reduced consumption of power.

The propellers, aeromotors, etc., actually known derive their efficiency from the resistance 35 which an air mass opposes to its being set in motion. The effective output is determined by the quantity of air which comes in direct contact with the surface which sets this air in motion, and by the speed v which the surface in 40 motion imparts to it. If F is the surface of the blades which set the air in motion, one has

$$W = k \cdot \rho \cdot F \cdot v^2$$

where W designates the power which must act 45 on a volume of air $F \cdot v$ in the time unit, to impart to it the speed v . As the total surface of the blades of a propeller is smaller than the surface of the circle described by the blades, the power of traction, for instance in the traction propellers, necessarily remains smaller than the power required to communicate the speed v to the air mass crossing the whole of the circular surface.

It is only the mass of air in direct contact with the surface of the blades which produces 55 an effect. According to the invention, success-

sive compressions and expansions are produced in the generated air current which transmit themselves in opposite directions starting from the point at which they are produced, with the speed of sound. In the application of the invention to aeromotors, the rate of revolution of the wheel of the aeromotor must be brought up to an appropriate speed by employment of sufficient power. In the case of a traction propeller driven by a motor, the traction power is equal to the power required to impart the speed v to an air mass 2 , say, 330 F . The air resistance being, in this latter case, designated by W_2 , one has

$$W_2: W = 330:v$$

The efficiency of the process according to the invention is based on the following considerations: Supposing, in a long tube of section F , a mobile surface occupying exactly the section of the tube, it is evident that when the surface displaces itself, and a corresponding body of air in the tube, the air cannot escape laterally. When the surface displaces itself at the speed v , the layers of air which are at a distance from the surface must progressively follow the same movement as it. A certain time is required t for a layer of air separated from the surface F by the distance l to take this motion. During this time, however, the surface F has described a path $t.v$, and consequently compressed a volume of air $1.F$ to the volume $(1-tv)F$. During this time, at the back of the surface in motion, an expansion or relaxation of air is produced, the volume of air $1.F$ having expanded to the volume $(1+tv)F$. The speed with which the surface movement imparts itself to the most distant air layers is equal to the speed of sound, and the resistance which the surface meets with is equal to the normal atmospheric pressure. If at a pressure of about $W_2=70.F.v \text{ kg}$. If the mobile surface stops, compression of the furthest removed air layers, situated on either side of the surface, terminates progressively, and the air resumes its normal density, and their movement transmits itself to air layers which are further away.

Supposing a tube having a length L and calculating the speed of sound as 330 m/sec. , the above resistance will only exist during the time

$$t = \frac{L}{330}$$

(or

$$\frac{2L}{330}$$

taking into account the duration of the propagation before and behind the surface F) from the start of the movement. If, after this period of time, the surface continues to displace itself whereas the air coming out of the tube can escape in all directions, the changes in density diminish toward zero. As a matter of fact, the compression and the expansion described which propagate themselves with the speed of sound, only take place within the tube. Variations of density which propagate themselves, can also produce themselves in the open air, if the weak duration of the movement is comparable to that of the sound oscillations. If the length L of the tube is so small that the time

$$t = \frac{L}{330}$$

is near to the duration of an oscillation of a

sound emitter, the compressions and expansions caused in the tube by the movement of the mobile surface during the time t will still propagate themselves, at the speed of sound, in the open air after having left the tube, whereas the air in the tube returns to a state of rest, when after a time

$$t = \frac{2L}{330}$$

the movement of the mobile surface has ceased. The resistance met by the mobile surface during the time t is again equal to $W_2=70.F.v \text{ kg}$.

The speed of the revolutions of the propeller 4 or of the disc 11 is predetermined in such a manner that the duration of the pulsations caused by these devices will be as nearly as possible the same as the duration of the sound oscillations. It is sufficient if a rate of $\leq 1/2000 \text{ sec.}$ exists which can be obtained by the peripheral speed of the revolution of the propeller 4 or of the discs 11 near to the speed of sound.

However, for reasons of practical realization, one may choose $U=k.330$, with $k<1$, U being the effective peripheral speed.

The following relations:

$$W_2=70.F.v$$

$$30 \quad t = \frac{L}{330} \leq \frac{1}{2000}$$

$$U=k.330$$

allow one to predetermine, in each case considered, the power, and the effective output, as well as the dimensions of the propeller or of the disc, the number of blades, the width and the pitch of the blades, the number of cells, etc.

The number of blades of the propeller 4 depends on the number of cells 9. The revolution speed 40 being suitably determined, the blades produce on one face, an air rarefaction, and on the other face, an air compression, like the mobile surface in the example described hereinabove.

If the number of revolutions of the propeller, 45 the width of the blades, and the number of cells 9 present a relation such that between the obturation of a cell by a blade and the reopening of the cell, the compression or the air expanded in the cell has not had time to transmit itself 50 to the exterior of the cell, that is to say, to come out of the cell, the effect is then identical with that of the example of the tube above given.

The device according to the invention is applicable to propellers in general, especially to 55 aeroplane propellers, to aeromotors, to the wheels of static parachutes, etc.

Fig. 5 shows schematically an application of the invention to an aeroplane wherein lifting surfaces are replaced by propellers according to 60 Fig. 1. It will be understood that one or more such similar propellers can be utilised as driving propellers for aeroplanes.

Having now fully described my said invention, what I claim and desire to secure by Letters Patent, is:

A blower or the like comprising a first air chamber, a first circular air compressing member positioned across a conforming air intake opening formed in a side of said first air chamber, a ventilator at the opposite end of said first chamber, said ventilator having a substantially axial intake conduit leading from said first chamber and an eccentric discharge conduit, a second air chamber at the opposite side of said ventilator 70 from said first air chamber and with which said

discharge conduit is connected, a second circular air compressing member positioned across a conforming air outlet opening formed in the outer side of said second air chamber, each of said air compressing members consisting of a pair of substantially similar slightly axially spaced elements each consisting of a circular rim having uniformly circumferentially spaced radial spokes which have relatively great width in the axial direction and a hub in which the radially inward ends of the spokes terminate, the spaces between adjacent spokes and the rim defining segmental air confining pockets, and a rotary disc substantially occupying the space between the said elements

and coaxial therewith, said disc being formed with uniformly circumferentially spaced segmental openings defining imperforate segmental shutters therebetween, the segmental openings being 5 slightly narrower than and the segmental shutters being slightly wider than the segmental spaces between the spokes of said elements in a circumferential direction, a common shaft journaled in the hubs of the elements of said first 10 and second members, and extending through the said first and second air chambers and on which the rotary disks are fixed, and means for driving said common shaft.

MAX RENDELSTEIN.
